UNITED STATES PATENT OFFICE.

ALFRED EDWARD RICHARDS, OF LEICESTER, ENGLAND, ASSIGNOR TO UNITED SHOE MACHINERY COMPANY, OF PATERSON, NEW JERSEY, A CORPORATION OF NEW JERSEY.

SHOE-SEWING MACHINE.

1,163,558.

Specification of Letters Patent.

Patented Dec. 7, 1915.

Application filed August 25, 1913. Serial No. 786,474.

To all whom it may concern:

Be it known that I, ALFRED E. RICHARDS, a subject of the King of Great Britain, residing at Leicester, in the county of Leicestershire, England, have invented certain new and useful Improvements in Shoe-Sewing Machines; and I do hereby declare the following to be a full, clear, and exact description of the invention, such as will enable others skilled in the art to which it appertains to make and use the same.

The present invention relates to sewing machines such as are used in the manufacture of boots and shoes for sewing together the upper and sole of a turn shoe, or the welt, upper and insole of a welt shoe.

The object of the invention is to provide a novel and improved machine which is adapted to operate upon an unlasted shoe, the sole or insole of which is provided with a channel, or channel lip by which the upper is secured to the sole.

The invention accordingly contemplates the provision, in a machine provided with a curved hook needle and co-operating stitch forming devices, of a work support adapted to enter an unlasted shoe and support successive parts of the sole margin as they come to the sewing point and opposed devices adapted to engage respectively the unlasted upper and the inside of the channel lip to hold them in correct position with relation to the stitch forming devices.

Since it is desirable that the upper, before being stitched to the channel lip, should be pressed down into the angle between the feather of the sole and the channel lip, it is preferred to arrange the upper-engaging device so that it shall have a wiping movement inward over the upper toward the channel lip to lay the upper into the angle between the feather and the lip, and finally hold it against the lip, thus permitting the needle to sew the two closely together at the base of the lip. It is also preferred to move the upper-engaging device in the direction of feed so that it may assist the needle, or other feeding devices in feeding the work.

The various features of the invention will be readily understood from an inspection of the accompanying drawings and the following detailed description of the mechanism illustrated therein.

In the drawings, Figure 1 is a side view of a machine embodying the features of the

invention in their preferred form; Fig. 2 is an enlarged side elevation showing the parts operating immediately upon the work; Fig. 3 is a horizontal section view on line 3—3 of Fig. 2 with certain parts broken away; Fig. 4 is a front elevation of the same, omitting the work supporting horn; Fig. 5 is a vertical section on line 5—5 of Fig. 3; and Fig. 6 is a vertical section showing a portion of the shoe in operative relationship to the guiding and stitch forming devices.

In the drawings, the invention is shown as embodied in a machine for sewing turn shoes which is provided with stitch forming devices having substantially the construction and mode of operation of the well-known Goodyear welt and turn sewing machine. The stitch forming devices are mounted on a head 2 and include the usual hook needle 3 and looper 4. The machine is provided with a work support adapted to enter an unlasted shoe and progressively engage that part of the inner face of the sole which is adjacent to the sewing point. As shown, the support is in the form of a horn 5 shaped to enter a shoe, and preferably so mounted that it may be rotated to bring different parts of the shoe into operative relationship with the sewing devices. The horn is also connected with a treadle by 80 which it may be depressed for the reception and removal of the work, and is also automatically depressed by mechanism to be hereinafter described to enable the work to be fed. As shown, the horn is provided 90 with a sleeve 6 that is received within a bore in a bracket 7 projecting from the base of the head 2 and surrounds a supporting spindle 8 upon which it is capable of being rotated, for which purpose a ball bearing 9 is provided between the lower end of the sleeve 6 and an enlargement 10 of the spindle 8. Relative vertical movement between the spindle and the sleeve is prevented by the boss 11 fixed to the spindle 8 by a bolt 13, 95 this boss engaging in a recess in the upper end of the sleeve. The sleeve 6 is of sufficient length to permit of an up and down motion in the bracket 7 and is raised and lowered by a toggle 14, 15 the upper end of 100 the link 14 being connected with the spindle 8 at 16 while the lower link 15 is pivoted at 17 in the bracket 7 and is in the form of a bell-crank lever the outwardly extending arm 18 of which is connected with a treadle 110

rod 20. A screw 21 threaded through the frame forms an abutment for the central joint of the toggle and acts as an adjustable stop to regulate the height to which the horn will be raised, this raising being accomplished by a spring 19 that connects the arm 18 of the bell-crank lever with the frame and tends to maintain the toggle straightened. The screw 21 is provided with a lock nut 22 to maintain it in the position to which it has been adjusted.

From the foregoing it will be understood that the curved horn 5 is normally held in raised position by the spring 19 but that it can be lowered for the removal, insertion or manipulation of the work by the "breaking" of the toggle by lowering the rod 20 through the operation of a treadle to which the rod is connected. The horn is curved as aforesaid so as to extend within the shoe and is provided at its upper end with a button 25 that forms a support for the shoe sole. In the present construction the button is circular in plan and its upper surface is plane.

It is to be understood that in the use of the machine constructed according to this invention for the manufacture of soled turn shoes the edge of the upper overlaps the edge of the sole and in this position they are presented to the machine to be sewn and are afterward turned inside out.

In the illustrated embodiment of the invention the work is fed by the needle 3 which is of the curved type that in penetrating moves in the arc of a circle. For thus feeding the work the needle carrying lever 42 is mounted on a bracket 43 depending from a slider 44 that is adapted to be moved horizontally toward the left hand side of the machine after the needle has penetrated the work to feed the work, suitable mechanism being provided to accomplish this movement. To allow the feeding movement of the work by the needle the horn is lowered and this is effected by connections between the needle-actuating mechanism and the horn-lowering device. These connections may comprise a link 45 connected at one end to the lever 46 by which the needle is oscillated through its arc and at the other end to an arm 47 loosely mounted at 17 on the stud or spindle on which is mounted the bell-crank lever forming the lower element 15 of the toggle. The lever 46 is pivoted at 48 to the machine frame and carries a cam roll 49 that stands in a groove cut in the side of a cam disk mounted on the main shaft. The movements thus imparted to the lever 46 are communicated to the needle by a link 50 universally jointed at one end to the needle-carrying lever 42 and at the other end to the lever 46. The universal joints permit the lateral movement of the needle to feed the work. The arm 47 has

adjustably secured to it, by a screw and slot connection, a plate 51 having a laterally projecting tappet 52 which operates on an extension 53 of the arm 18 of the bell-crank lever 15, 18 and sufficient "lost motion" is provided between the contacting surfaces to provide a lowering of the horn merely sufficient to enable the work to be fed freely. The adjustment of the plate 51 on the arm 47 enables the operator to vary at will the extent to which the horn is lowered during the feeding movement. To prevent the treadle rod from being moved while the horn is automatically lowered for the feeding of the work the connection between the treadle rod 20 and the arm 18 of the bell-crank lever is constituted by a pin 54 projecting from the latter that enters a slot 55 in the treadle rod which is normally maintained raised by a spring 56 that connects it with a projection upon the frame. A stud 57 carried by the treadle rod 20 limits its upward movement by contacting with the said projection.

A channel lip support 70 is formed by a bracket 72 that is fixed to the machine frame just behind the horn top and has an extension projecting forwardly from its upper end sufficiently to overlie the top of the horn. This extension is provided with a downwardly projecting lug 74 that is shaped to support the inner side of the channel lip against the action of the needle 3 and of a clamping, pressing or wiping device 75. The said lug 74 is proportioned so as to project downward to support the whole of that portion of the channel lip upon which it acts but as the needle passes underneath the said supporting lug when penetrating the work to form a stitch and as the needle remains in that position during the feeding movement, the said lug is cut away at its center so as to clear the needle and thus at this part projects downward to support only the upper portion of the channel lip 110 and not the base. Thus the needle may pass freely under the lug as it moves to feed the work.

In order that the upper material may be sewed as closely as possible to the base of the channel lip a special form of presser foot or clamp 75 is provided to move forward, and to wipe over and clamp the upper material tightly against the base of the lip of the channel and preferably clamp 75 is of sufficient breadth to clamp the upper to the lip on both sides of the place at which the needle will operate. This clamp is cut away at 76 so that it does not clamp in front of the needle and its acting front edges are serrated as shown in Fig. 3 in order that it may obtain a better grip of the material at those places where it acts to clamp the upper laterally against the channel lip that is sustained by the support 70. 133

Obviously during the feeding of the work this clamp will either have to be retracted to release the work for feeding or will have to move with the work during the feeding operation. In the present instance it is preferred that it should operate in the latter manner and so assist in feeding the work and accordingly means are provided to correlate its movements with those of the needle.

The clamp is formed upon the end of a slide bar 78 which is carried in guideways in a carrier 79 (Fig. 2) and this slide bar 78 is normally held in retracted position by means of a spring 80, Figs. 3 and 5, contacting at its rear end with the slide bar 78 and at its forward end with a portion of the carrier 79 in which the slide bar moves. The rear end of the slide bar projects behind the rear of the carrier as in Fig. 2 and is adapted to contact with the upper end of a lever 82 pivoted to a bar 83 adjustably mounted upon the frame of the machine, the end of the lever below its pivot being attached to a spring 85 which at its other end is attached to the frame of the machine. This spring is strong enough to overcome the action of the spring 80 acting between the slide bar 78 and its carrier 79 so that were it not for other means acting upon the slide bar the latter would normally be held forward in clamping position. This, however, is not desired and accordingly there is fixed upon the lever pivot a curved arm 86 having at its upper end a roll 88 adapted to contact with an edge cam 90 carried by the spindle of the needle segment 42, the cam being so located upon the segment and so shaped that when the needle 3 is out of the work the cam will act to throw the upper end of the lever 82 rearwardly against the action of its spring 85 and so will permit the slide bar spring 80 to act to retract the slide bar, and consequently the clamp, from clamping position. It will be noticed that the clamp is moved yieldingly both toward the work and away from it.

In order that the clamp may be given lateral movement to accompany the needle, in its feeding action the carrier 79 upon which the slide bar 78 is mounted is itself mounted in grooves Fig. 5 at right angles to the guideways by which it carries the slide bar, these grooves being formed upon a frame 92, which is carried by, and is capable (by means of a slot and a screw provided with a handled nut 93) of vertical adjustment with relation to the head 2 of the machine.

60 The carrier that controls the lateral position of the clamp is normally held in one direction by means of a spring 94 attached at one end to a pin fixed to the carrier and at the other end to a pin fixed to the vertically adjustable frame 92. Mounted upon 65 the bracket 43 is a bent arm 95 whose free

end projects backwardly and downwardly to one side of the slide bar carrying guideways in the carrier, the arrangement being such that the carrier 79 is moved positively by the bent arm 95 in the direction to feed 70 the work and is yieldingly returned by its spring 94 to initial position.

The operation of the machine is as follows: The work is placed in the machine with the channel lip of the sole and the margin of the upper located between the projecting lug 74 of the channel lip support 70 and the feeding clamp 75, the extremities of the channel lip support being permitted to rest upon the sole. The upper is manipulated by the fingers into the correct position, gaged vertically, it may be by the neck of support 70, and then the clamp 75 advances and wipes the upper over the feather and clamps it against the channel lip which is supported by the lug 74; the needle at the same time advancing and finally penetrating the work. After this the horn drops to release the work. The needle then moves laterally to feed the work and the clamp cooperates with it, maintaining a yielding pressure on the margin of the upper that permits the work to slide over the surface of the channel lip support which is made sufficiently wide to support the lip adequately during the whole of the feeding stroke. At the finish of the feeding stroke the horn rises to support the work while the looper operates, the clamp then moves backward to release its grip, and finally both needle and clamp are returned laterally of the machine to their starting position.

While the invention has been shown and described as embodied in a turn shoe sewing machine in which the stitch forming devices are constructed and operated to form a chain stitch, it will be understood that it is not confined in its application to machines for sewing turn shoes or to chainstitch machines. It will also be understood that the broader features of the invention are not limited to the specific construction shown and described and that the construction and arrangement of the parts may be varied and modified without departing from the invention. 110 115 120

Having explained the nature and object of the invention and specifically described one form of mechanism in which it may be embodied, what is claimed is:—

1. A shoe sewing machine having, in combination, stitch forming devices including a needle and operating mechanism therefor, a work supporting rotatable horn adapted to enter an unlasted shoe and support successive portions of the sole margin and permit the shoe to be moved with relation to the support, and opposed devices arranged to engage respectively the upper and the inside of the channel lip to hold them in 125 120

- proper position for the passage of the needle through the margin of the upper and through the between substance. 65
2. A shoe sewing machine having, in combination, stitch forming devices including a needle and operating mechanism therefor, a work support adapted to enter an unlasted shoe and support successive portions of the sole margin and permit the shoe to be moved 10 with relation to the support, a guide for engaging the inside of the channel lip, a wiper arranged to move over the upper toward the channel lip, and means for actuating the wiper. 70
15. 3. A shoe sewing machine having, in combination, stitch forming devices including a needle and operating mechanism therefor, a work supporting horn adapted to enter an unlasted shoe and support successive portions of the sole margin, a guide for engaging the inside of the channel lip, an upper-engaging device, and means for moving the upper-engaging device in the direction of the feed during the feed of the work. 75
20. 4. A shoe sewing machine having, in combination, stitch forming devices including a needle, operating mechanism therefor, including means for actuating the needle to feed the work, a work support adapted to enter an unlasted shoe and support successive portions of the sole margin, a guide for engaging the inside of the channel lip, an upper-engaging device, and means for moving the upper-engaging device with the needle during the feed. 80
25. 5. A shoe sewing machine having, in combination, stitch forming devices including a needle and operating mechanism therefor, an upper-engaging device, means for pressing 40 the device yieldingly against the upper and connections between said means and the needle actuating mechanism for rendering said means inactive when the needle is retracted. 85
30. 6. A shoe sewing machine having, in combination, stitch forming devices including a curved needle and operating mechanism therefor, a sole support adapted to extend within an unlasted shoe and support successive portions of the sole margin, and a member 45 having a wiping motion in contact with the marginal portion of the upper and cooperating with the support to hold the upper against the feather of the sole and in such relation to the curved needle that the 50 needle will pierce both the margin of the upper and the sole in the angle between the feather and the body of the sole. 100
35. 7. A shoe sewing machine having, in combination, stitch forming devices including a curved needle and operating mechanism therefor, a sole support adapted to support successive portions of the sole margin within an unlasted shoe, and a clamping member having a slot extending in the direction of 55 the needle movement and an upper-pressing end face, and means for actuating the clamping member to wipe the upper into the angle between the feather and the shoulder of the sole and hold it in position for the needle to pierce the upper and enter the sole at the base of the shoulder. 105
40. 8. A shoe sewing machine having, in combination, stitch forming devices including a curved needle and operating mechanism therefor, a horn adapted to support successive portions of the sole margin within an unlasted shoe, a clamping member having a slot extending in the direction of the needle movement and an upper-pressing end face, means for actuating the clamping member to wipe the upper into the angle between the shoulder and the sole and hold it in position for the needle to enter the sole at the base of the shoulder, and means for automatically lowering the horn to prevent the curved needle from binding the work on the sole supporting face of the horn. 110
45. 9. A shoe sewing machine having, in combination, stitch forming devices including a curved needle, operating mechanism therefor, means to cause the needle to feed the work, a sole support adapted to support successive portions of the sole margin within an unlasted shoe, a clamping member, means for operating the clamping member to force 90 the upper into the angle between the feather and shoulder of the sole and hold it in position for the needle to enter at the base of the shoulder, and connections through which the clamping member is moved with the needle 95 to feed the work. 100
50. 10. A shoe sewing machine having, in combination, stitch forming devices including a curved needle and operating mechanism therefor, a sole support adapted to extend within an unlasted shoe and support successive portions of the sole margin, and a member extending across the edge of the upper and having a down-turned end between which and the sole support the sole is confined and which engages and supports the channel lip against the outward thrust of the needle. 105
55. 11. A shoe sewing machine having, in combination, stitch forming devices including a curved needle and operating mechanism therefor, a sole support adapted to extend within an unlasted shoe and support successive portions of the sole margin as the shoe is moved with relation to the sole support and a channel lip support arranged to engage the channel lip on opposite sides of the needle path and support the channel lip against the thrust of the needle. 110
60. 12. A shoe sewing machine having, in combination, stitch forming devices including a curved needle, operating mechanism therefor including provision for operating 115
65. 13. A shoe sewing machine having, in combination, stitch forming devices including a curved needle and operating mechanism therefor, a sole support adapted to extend within an unlasted shoe and support successive portions of the sole margin as the shoe is moved with relation to the sole support and a channel lip support arranged to engage the channel lip on opposite sides of the needle path and support the channel lip against the thrust of the needle. 120
70. 14. A shoe sewing machine having, in combination, stitch forming devices including a curved needle and operating mechanism therefor, a sole support adapted to extend within an unlasted shoe and support successive portions of the sole margin as the shoe is moved with relation to the sole support and a channel lip support arranged to engage the channel lip on opposite sides of the needle path and support the channel lip against the thrust of the needle. 125

the needle to feed the work, and a channel lip support immovable in the direction of feed for supporting the lip against the thrust of the needle having a slot in its sole-engaging face to permit the passage of the needle and its movement to feed the work.

13. A shoe sewing machine having, in combination, stitch forming devices including a curved needle and operating mechanism therefor, a channel guide, a sole supporting horn arranged to progressively engage the sole within an unlasted shoe and permit the shoe to be moved with relation to the supporting guide, and an upper-engag-

ing device movable toward and from the channel guide.

14. A shoe sewing machine having, in combination, stitch forming devices including a curved needle and operating mechanism therefor, a channel guide, a sole supporting horn arranged to progressively engage the sole within an unlasted shoe, an upper-engaging device, and a gage for the edge of the upper.
